UNITED STATES PATENT OFFICE.

CARLOS A. SCHMIDT, OF OAKLAND, CALIFORNIA.

DESIGN FOR A VEHICLE SIGNAL CASING.

Application filed October 13, 1928. Serial No. 28,481. Term of patent 14 years.

To all whom it may concern:

Be it known that I, CARLOS A. SCHMIDT, a citizen of the Republic of Chili, South America, and a resident of Oakland, in the county of Alameda and State of California, have invented a new, original, and ornamental Design for Vehicle Signal Casings, of which the following is a specification, reference being had to the accompanying drawing, forming part thereof.

Figure 1 is a front elevation of a vehicle signal casing embodying my new design.

Figure 2 is a top plan of the same.

I claim:

The ornamental design for a vehicle signal casing, substantially as shown.

CARLOS A. SCHMIDT.
